UNITED STATES PATENT OFFICE

JAMES UNDERWOOD, OF BANGOR, AND JOHN J. BARNET, OF EASTON, PENNSYLVANIA,
ASSIGNORS TO JULIUS KAYSER & CO., OF NEW YORK, N. Y., A CORPORATION OF NEW
YORK

APPARATUS AND METHOD FOR EXAMINING MATERIAL

Application filed October 18, 1928. Serial No. 313,232.

This invention relates to improvements in a method of and apparatus for use in examining materials, such as knitted or woven textile goods.

5 One object of this invention is to provide a method whereby the material to be examined or inspected is held between a translucent and a transparent member which co-operate to flatten the material, and a source 10 of light being applied behind the translucent member while the material is inspected or examined through the transparent member.

A further object of this invention is to provide an examining table having an illuminated translucent surface upon which the material may be smoothed by means of a transparent member.

Still further objects of this invention are the provision of means whereby the material 20 to be examined may be conveniently clamped upon a translucent table illuminated from below, the provision of improved means for clamping the material without danger of damaging the same, the provision of improved means for illuminating the under side 25 of the table, and the provision of an improved smoothing implement of transparent material.

With these and other objects in view the 30 invention consists in the novel construction and arrangement of parts hereinafter described, illustrated in the accompanying drawings and particularly pointed out in the appended claims, and in the novel method hereinafter described and particularly pointed out in the said claims.

It should be understood that various 40 changes may be made in the constructional details of the apparatus without departing from the spirit of the invention or sacrificing any of the advantages thereof.

In the drawings Figure 1 is a vertical sectional view of the apparatus;

45 Fig. 2 is an end view of the apparatus showing the upper part thereof drawn to a smaller scale;

Fig. 3 is a plan view of a part of the apparatus;

50 Fig. 4 is a front view of the same; and,

Fig. 5 is a view, partly in section, of the transparent smoothing implement.

It will be understood that the apparatus may be adapted for use by a single inspector or examiner, but in its preferred form the apparatus is built with a plurality of inspecting or examining stations mounted upon the same frame as shown at Figs. 3 and 4 of the drawings.

The apparatus is made with a box-like structure or casing 10 which may be either subdivided or may be open from end to end in the case of a multiple station apparatus. This structure 10 is mounted upon supporting legs 11, braced together near their lower 55 ends by means of cross bars 12 and a longitudinal bar 13, which latter carries brackets 14 for the purpose hereinafter described.

The structure 10 is formed at each examining station with an opening 15 within which is 60 mounted a translucent panel consisting of two glass plates 16, 17, the upper plate 16 being of ground glass with its smooth side uppermost and the under plate 17 being of plain transparent glass, and surrounding the glass 65 plates 16, 17 on all four edges are strips 18 of soft rubber having exposed edges for contact with the material being examined, so as to avoid the possibility of damage to such goods. Mounted on the backboard 19 and

projecting forwardly into the box-like structure 10 are a number of electric lamps 20 by 70 means of which the interior of the structure is illuminated and the internal surfaces of the structure 10 are preferably painted white or 75 are otherwise provided with light-reflecting surfaces to facilitate the proper and uniform illumination of the glass plates 16, 17. Behind the inclined illuminated panels the structure 10 has a number of hinged covers 21 to

give convenient access to the lamps 20 and to receptacles 22 provided with floors 23 at the 80 end of the rows of lamps.

For conveniently clamping the material to be examined upon the inclined illuminated panel there is provided at the right-hand side of each of such panels a rubber or other like soft cushion 24 upon which one end of the material may be held by means of a clamp 95 25 pivotally mounted in a bracket 26 on the 100

upper part of the structure 10. For the operation of this clamp a rod 27 extends through the upper and lower part of the structure and has a spring 28 in compression between a collar 29 on the rod 27 and a fixed collar 30 engaging the under side of the inclined part of the structure 10, so that the clamp 25 is normally held by spring action upon the cushion 24 or upon the material clamped between the parts 24 and 25. The lower part of the rod 27 has a collar 31 engaged by the forked end 32 of a lever 33 fulcrumed at 34 and connected by means of a rod 35 to a treadle or foot-control lever 36 pivotally mounted in the brackets 14 hereinbefore referred to, so that depression of the pedal 36 raises the clamp 25 which latter is returned to its clamping position by the action of the spring 28 as soon as the treadle is released.

The smoothening implement 37 consists of a plate of beveled transparent glass having a handle 38, and as this implement is moved over the material being inspected it serves to flatten or smooth the material and thus facilitate proper inspection and the detection of flaws, irregularities, or other imperfections. In Fig. 3 of the drawings the implement 37 is shown in use straightening or smoothing the leg portion of a stocking supported on the inclined illuminated panel and held by the end clamp 25.

Although the above specification and the accompanying drawings disclose the best mode in which we have contemplated embodying our invention, we desire to be in no way limited to the details of such disclosure, for in the further practical application of our invention many changes in form and construction may be made as circumstances require or experience suggests without departing from the spirit of the invention within the scope of the appended claims.

What we claim is:

45 1. A method of examining material which comprises supporting the material upon a translucent member, illuminating said member, applying to the material a flat transparent member, moving the transparent member over the surface of the material to smooth the same, and examining the material by observation thereof through the transparent member.

55 2. A method of examining material which comprises supporting the material upon the upper side of a flat translucent member clamping one edge of the material, applying a source of illumination below such member, applying above the material a flat transparent member, moving the transparent member relatively to said clamped edge and over the surface of the material to smooth and flatten the same, and examining the material by observation through the transparent member.

3. Apparatus for use in inspecting material comprising a box-like structure, a translucent panel therein, foot-operated means for use in clamping one edge of the material upon the panel, and relatively movable means for smoothing the free portion of the material upon the panel.

4. Apparatus for use in examining material comprising a translucent inclined panel, a spring clamp for holding one edge of the material adjacent to the panel, foot-operated means for releasing the said clamp, and relatively movable means for smoothing the free part of the material upon the panel.

5. Apparatus for use in examining material comprising a box-like structure, an inclined translucent panel in the structure, means within the structure for illuminating the under side of the panel, clamping means for holding one edge of the material adjacent to the panel, and a relatively movable transparent device for smoothing the free portion of the material upon the translucent panel.

6. Apparatus for use in examining material comprising an inclined illuminated table, soft marginal strips surrounding said table, means for clamping one edge of each piece of material upon one of said marginal strips, and means for smoothing the free portion of the material upon said table.

7. Apparatus for use in examining material comprising a box-like structure, an inclined translucent panel in the upper part of the structure, a source of illumination within the structure, soft marginal strips surrounding the panel, a clamp for holding one marginal edge of the material adjacent one side of the panel, and means for smoothing the free portion of the material upon the surface of the panel.

In testimony whereof we have signed our names to this specification.

JAMES UNDERWOOD.
JOHN J. BARNET.
